UNITED STATES PATENT OFFICE

134,698

DESIGN FOR A TEXTILE FABRIC

Samuel N. Kirschenbaum, Woodmere, and Benjamin Frank, New York, N. Y.

Application November 21, 1942, Serial No. 108,833

Term of patent 3½ years

To all whom it may concern:

Be it known that we, Samuel N. Kirschenbaum and Benjamin Frank, both citizens of the United States, residing at Woodmere, L. I., county of Nassau, State of New York, and Manhattan, county of New York, State of New York, respectively, have invented a new, original, and ornamental Design for a Textile Fabric, of which the following is a specification, reference being had to the accompanying drawing, forming part thereof, wherein the figure is a plan view of a textile fabric, showing our new design.

The figure shows a full width of the fabric, the design being repeated horizontally.

We claim:

The ornamental design for a textile fabric, substantially as shown and described.

SAMUEL N. KIRSCHENBAUM.
BENJAMIN FRANK.
